UNITED STATES PATENT OFFICE.

WILLIAM G. FAGLIE, OF CANTON, TEXAS.

CRANK-SHAFT GRINDER.

Application filed April 30, 1926. Serial No. 105,755.

This invention relates to new and useful improvements in crank shaft grinders.

The object of the invention is to provide a tool for grinding the bearing surfaces of a crank shaft to a true circular circumference.

A further object of the invention is to provide means for use in connection with the tool for finishing and polishing the bearing surfaces which have been ground.

A particular object of the invention is to provide a pair of semicircular grinding members having curvilinear abrading faces for engaging the work and conforming to the arc of the bearing.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is a longitudinal sectional view of a tool constructed in accordance with my invention,

Fig. 2 is a plan view of the same with a portion in section,

Fig. 3 is a perspective view of one of the grinding sectors, and

Fig. 4 is a transverse sectional view of the tool used as a finisher.

In the drawings, the numeral 10 designates an arcuate yoke having a central tubular handle 11 extending from its convex side. The yoke has spaced ears 12 at each end. An arcuate keeper 13, complementary to the yoke has ears 14 at each end engaging between the ears 12. At one side of the frame or head formed by the yoke and keeper, the ears are connected by a rivet 15, whereby the said keeper is hinged to the yoke; while at the other side a bolt 16 passed through the ears is secured by a wing nut 17, thus latching the parts together.

Within the head a pair of semicircular grinding sectors 18 and 19, respectively, are mounted, their curvature corresponding generally to the curvature of the yoke and keeper. The sector 18 has a sump or socket 18' at

the center of its back for receiving the reduced end of an adjusting stem 20 screw-threaded in the tubular handle 11 and having a grip 21 on its outer end. The sector 19 has a sump or socket 19' at the center of its back 55 for receiving an adjusting screw 22 threaded through the keeper.

Each sector has its concaved face provided with grinding serrations or is otherwise formed for carrying out a grinding operation, when rotated. The sectors are adjustable toward each other by means of the stem 20 and screw 22, and by which latter said sector may be pressed against the work.

In using the tool the nut 17 is removed 65 and the bolt 16 withdrawn, whereby the keeper 13 may be swung outwardly as is shown in dotted lines in Fig. 1. The parts are engaged around the bearing element A of the crank shaft, which is illustrated as 70 having a flat portion B, and are secured by the bolt 16. The stem 20 and screw 22 are adjusted to bring the grinding faces of the sectors into contact with the bearing and the handle 11 is then grasped and the tool 75 swung or rotated. As the surface is ground the sectors are adjusted and the grinding continued until the bearing surface is brought to a true circle.

It will be understood that the concave 80 grinding surfaces of the sectors are like files and may vary in degrees of coarseness or fineness. After the grinding operation is complete the head of the tool is opened and the sectors removed. Other sectors 18^a and 85 19^a (Fig. 4), having strips of emery cloth or other abrading material on their concaved faces, are inserted in the tool and the bearing element A is then polished and finished.

Sectors for different diameters may, of course, be provided. The tool is simple, efficient and easy to operate.

Various changes in the size and shape of the different parts, as well as modifications 95 and alterations, may be made within the scope of the appended claim.

What I claim, is:

A crank shaft grinding tool comprising an arcuate yoke having an elongated tubular 100

handle extended centrally therefrom, a stem screw threaded into said handle and extending through the yoke, operating means for the screw at the free end of the handle, a semi-circular grinding sector disposed in the yoke and engaging the inner end of said screw, an arcuate keeper hinged and latched to the yoke in a plane at a right angle to

the axis of the screw, a second semi-circular grinding sector disposed in the keeper, and an adjusting screw threaded into the keeper in alinement with the stem screw and engaging the second sector. ¹⁰

In testimony whereof I affix my signature.

WILLIAM G. FAGLIE.
